[57] CLAIM

The ornamental design for a load handling vehicle, as shown and described.

DESCRIPTION

FIG. 1 is a right side elevational view of a handling vehicle showing my new design (The portion of the article depicted in broken lines forms no part of the design);

FIG. 2 is a top plan view thereof;

FIG. 3 is a left side elevational view thereof;

FIG. 4 is a front elevational view thereof; and

FIG. 5 is a rear elevational view thereof.

FIG. 6 is a top and right-front perspective view thereof shown without environmental structures; and,

FIG. 7 is a top and left-rear perspective view thereof shown without environmental structures.
